UNITED STATES PATENT OFFICE

GUSTAVE L. KAYDEN, OF NEW YORK, N. Y.

AIRSHIP

Application filed August 23, 1930. Serial No. 477,275.

This invention relates to airships and particularly, to that type designed to rise and descend substantially vertically with a minimum amount of horizontal movement, to hover in the air, and to land in a comparatively small space.

My invention contemplates the provision of a series of movable wings designed to be operated in the direction required to produce fluid pressure for the proper manipulation of the ship.

My invention further contemplates the provision of simple means designed for sufficiently rapid continuous movement for the purpose intended, of such construction that it is not likely to get out of order, and positive in operation, to cause the wing to operate in a manner which may be best described as a substantially semi-circular downward rotary movement alternating with an upright feathering movement. In other words, the wing is caused to rise during its movement substantially vertically to feather the wing, and then is swung rapidly about its lower end through an angle of substantially 180° to produce a rapid beating action to produce the pressure required to support and operate the ship.

My invention contemplates the arrangement of such wings in the proper position for control by the operator, and for producing the required effect to lift the airship and to maintain it at any desired altitude. My invention further contemplates the provision of means for operating a series of such wings in proper timed relation so that the lifting effect on the airship may be maintained at all times as desired during the flight thereof, and the provision of means for cushioning the wing when the direction of its movement is changed.

The various objects of my invention will be clear from the description which follows, and from the drawings, in which,

Fig. 1 is a side elevation of my improved ship, part of the right hand portion being broken away, and showing the arrangement of the wings and the operating mechanism therefor.

Fig. 2 is a top plan view of the gearing con-

nection between the source of power and the wing.

Fig. 3 is a front elevation of the airship, showing the wings and the operating mechanism therefor, and showing particularly, how the wings may be arranged to produce a continuous supporting or lifting effect.

Fig. 4 is a front view of a modified form of the wing operating member.

Fig. 5 is a plan view of the same.

Fig. 6 is a front view of a casing for receiving the wing during the latter portion of its operative stroke, and for cushioning the wing just prior to the change of direction of movement thereof.

Fig. 7 is a diagrammatic perspective view of my improved ship, showing a modified form of the frame therefor, and

Fig. 8 is a cross section of a modified form of the wing.

In that embodiment of my invention illustrated by way of example, any suitably braced frame as 10 of light but durable material in the form of a cage, as shown in Fig. 7 or in other forms, and suitable for supporting the various instrumentalities soon to be described, may be provided.

As illustrated in Figs. 1 and 3, the frame 10 may consist of a number of spaced upright members 11, each provided with extending arms as 12, in which the mechanism for supporting the wings and for operating said wings may be mounted. The upright members 11 may be suitably braced and connected as by means of horizontal braces 13 and 14 as well as intermediate braces, should they be required, and said members 11 may be multiplied and as many arranged in the frame as may be found convenient or desirable.

One of the important features of my invention is the mechanism for operating each of the wings 15. A series of such wings are provided and the operating mechanism therefor is so designed that the tip of the wing rotates downwardly about its lower edge as a pivot, through a substantially semi-circular path designated by the numeral 16 in Fig. 3, and is then feathered upwardly, the rotational and linear movements alternately and

the movement of the wing being continuous. The path 16 consists, therefore, of a portion which is approximately a semi-circle, as shown by the dotted lines 17, which semi-circle is closed by its vertical diameter 18.

It will be seen that during the downward rotational movement of the wing through the semi-circular path 17, a beating action is obtained whereby sufficient pressure may be generated to lift and support the ship, the wings being made of sufficient size and area for that purpose and a sufficient number of such wings being provided. It will further be understood that the wing should be symmetrical about its center line since it is reversed in position at the completion of each movement thereof. Each of the wings terminates in an inner end plate 19 (Figs. 4, 5 and 8), to which is secured an annular toothed member 20 in the form of a pair of combined parallel racks and arcuate gear portions joining the racks. In other words, the member 20 is of substantially rectangular outline but has arcuate ends, being also provided with an opening as 21 therein, the edges of which are parallel to the pitch line of the teeth of said member. For supporting the toothed member 20 and the wing secured thereto, I prefer to provide a shaft as 22 mounted upon the arm 12 and carrying thereon a suitable roller 23 which is inserted into and engages the edge 24 of the opening 21 at all times.

The gear wheel 25 is mounted upon a shaft 26 also supported in an arm 12, and at a fixed distance from the shaft 22. By reason of the fixed relation of the axes of the shafts 26 and 22, the teeth of the gear wheel and of the toothed member are maintained permanently in mesh and rotation of the gear wheel causes operation of the toothed member, no matter which part of the edge 24 of the opening 21 is engaged by the roller 23. When either of the arcuate ends 27 or 28 of the member 20 is in engagement with the gear wheel, it will be seen that a rapid rotation of the member 20 is effected through an angle of substantially 180° . When the wheel 25 meshes with the straight or rack portions 29 or 30 of the member 20, then said member, together with the wing carried thereby, is given a somewhat slower upward movement. Continuous rotation of the gear wheel 25 therefore operates the member 20 alternately through a downward rotational movement and through an upward feathering movement substantially in the plane of the wing.

It will be understood that during the upward portion of the movement of the wing, corresponding to the path portion 18, substantially no air pressure is created, but that when the toothed lower curved end as 28, of the member 20 comes into engagement with the gear teeth, then the wing is rapidly rotated downwardly through the path 17, and

beats downwardly upon and through the air and to produce the required lifting effect. The roller 23 during this movement serves not only as a support for the wing but maintains the teeth of the member 20 in engagement with the gear 25, and also acts as a pivot for the wing. Since the member 20 is reversed after each stroke, I prefer to make said member together with the wing 15 symmetrical about a plane passing through the axis thereof.

As illustrated in Figs. 4 and 5, I have provided means for more gradually changing the direction of movement of the wing from its semi-circular path 17 to its upward path 18, than is possible, when the annular rack or toothed member 20 illustrated in Fig. 3 is used. In the modified form shown in Figs. 4 and 5, the toothed member 31 comprises the parallel rack portions 32 and 33 both parallel to the axis of the wing, and includes the arcuate ends 34 and 35 which are somewhat less in extent than a semi-circle, as well as the inclined straight or arcuate portions 36, 37, 38 and 39 joining the respective arcuate ends 34 and straight portions and being tangent thereto. The edge 40 of the opening 41 in the member 31 is, of course, parallel to and concentric with the pitch line of the teeth of said member, as has been explained in connection with the member 20. In this modification, the speed of rotation of the wing through the path portion 17 remains unaffected, but the change in direction of movement of the wing due to the inclined portions 36, 37, 38 and 39 is not effected so rapidly, but more gradually, so that shock and wear upon the mechanism may be lessened.

This purpose may also be attained in various other ways. For example, the shock upon the mechanism due to the change of direction from the path 17 to the path 18 may be largely absorbed by the use of suitable shock-absorbing devices. As illustrated, such a device comprises the headed pin 45, mounted for horizontal movement in a suitable opening 46 in the upright frame member 11, and yieldable when the edge of the plate 19 strikes it. The pressure of the wing or end plate 19 upon the pin, is absorbed by a suitable spring 47 coiled thereabout, and abutting at one end against the pin head and at its other end against the frame.

Said spring serves to maintain the pin in the proper position to resist the latter part of the rotational movement of said wing and thereby to absorb the shock which may be caused by a sudden change of direction of movement from rotary to linear.

As shown in Fig. 6, an air cushion may be provided in the latter part of the downward rotational movement of the wing for the same purpose, in place of the spring 47 and pin, or in addition thereto. In this form of

cushioning means, I provide a casing comprising the substantially vertical innermost wall 50, the arcuate bottom wall 51, and the pair of side walls 52 joining the bottom and inner walls 50 and 51. The outer edges of the walls 52 are inclined upwardly and inwardly toward the pivot of the wing, and the bottom wall 51 is provided with suitable openings, holes or slits 53. The wing 15 and the casing are of about the same dimensions, so that as the wing enters said casing, it acts as a piston to compress the air caught between the wing and the walls of the casing whereby a cushioning effect upon the wing is obtained. The air in the casing is forced, on the further downward movement of the wing in the casing, downwardly through the slits or holes 53, whereby the air caught in the casing is ejected from the casing with considerable velocity downwardly, and thereby acts to produce a lifting effect upon the ship.

As shown in Fig. 8, the wing 55 may be provided with similar curved ends 56, arranged symmetrically about the center line of the wing, to produce greater pressure upon the air in its downward stroke, about its left edge. Said wing may be built up of suitable light material, being provided with internal braces 57 covered with fabric 58 stretched thereupon and suitably stiffened in a manner which is well known and hence need not be further described.

It is desirable that at least one pair, and if desired, more than one pair of wings be operative at all times. Toward this end, the operation of the various members 20 may be timed in a manner somewhat similar to the timing of the pistons in a four-cycle internal combustion engine. For example, the uppermost pair 75 of wings, are in the early part of their operative stroke while the lowermost pair 76 are in the latter part of said stroke. The third set 77 from the top, are just finishing their inoperative strokes while the second pair 78 is about to start its inoperative stroke. It will be understood that as many pairs of wings as may be found desirable may be used, since my invention contemplates the use of a plurality of sets of wings so timed that sufficient pressure is obtained at all times to create the desired lifting effect.

As shown in Figs. 2, 3 and 7, the wings of an opposed pair are simultaneously operated in opposite directions to obtain proper balance of the ship. Each of such pair of wings may be operated by an independent motor should it be desired to do so but I have shown a single motor 60 for operating all of the wings. The motor shaft 61 is connected at its ends by suitable worms 62 to the worm wheel, gears 63 and 64 on the upright shafts 65 and 66. Each of said shafts 65 and 66 carries a series of bevel gears 67 and 68,

meshing respectively with similar gears 69 and 70 on the respective drive shafts 26. The gear 25 on the same shaft 26 engages the toothed member 20 which is in turn supported, as has been previously explained, by the shaft 22 and the roller 23 thereon. Since the corresponding simultaneously operated wing 115 of the pair should rotate in the opposite direction, a second gear 125 engages the gear 25 and operates the member 20, all as shown in Fig. 2.

Similarly, that shaft 26 carrying the bevel gear 70 may extend across the frame and carries a gear wheel 25 meshing with a toothed member 20.

By means of this arrangement of gearing, it will be seen that two pairs of wings are simultaneously operated, each pair consisting of wings rotating in opposite directions to properly balance the machine during its operation. The various shafts 26 for aligned wings may be combined, if desired, but as shown, a separate shaft is used since a single shaft could not cross the shafts 65 and 66 if bevel gears are used. It is to be understood that the gearing shown and described for connecting the motor 60 to the gears 20 is merely illustrative, and that any suitable arrangement of gearing may be substituted therefor. A suitable fuselage as 79 may be secured to the frame, or said frame, as illustrated in Fig. 7, may be made of sufficient extent to provide a cabin or cage for the operator, and provided with suitable controls. Forward or rearward movement of the ship may be obtained in the customary manner by means of suitable propellers in a manner well known in the art and hence which need not be described nor shown.

It will be seen that I have provided comparatively simple mechanism for operating the wings of an airship in the proper direction to cause lifting pressure to raise the ship to the desired height and to maintain it at such height, that the ship may rise and descend substantially vertically, and that the mechanism is well suited to the purposes for which it is intended.

While I have shown and described certain specific embodiments of my invention, I do not wish to be understood as limiting myself thereto since I intend to claim my invention as broadly as may be permitted by the state of the prior art and the terms of the appended claims.

I claim:

1. The combination with an airship wing, of an end plate therefor, a toothed elongated gear member having a central opening therein parallel to the pitch line of the teeth of said member, a gear wheel in operative engagement with said gear member, and means movable relatively to the edges of said opening, but fixed relatively to said gear wheel for

maintaining said gear member in constant engagement with said gear wheel.

2. The combination with the wing of an airship, of an elongated toothed gear member for rotating said wing downwardly through an angle of approximately 180° from the initial position thereof, and for feathering said wing upwardly into initial position, the pitch line for the teeth of said member being of closed outline, comprising straight line portions and arcuate portions, said gear member having an opening therein arranged inwardly of said pitch line, the edge of the opening being parallel to said pitch line, a fixed roller engaging the edge of said opening for maintaining the operative teeth of said gear member at a predetermined fixed distance from said roller, and a gear wheel engaging the operative teeth of said gear member.

3. Means for operating the wing of an airship downwardly through an angle of approximately 180° from the initial position thereof about a fixed pivot, and then bodily upwardly relatively to said pivot in substantially the plane of the wing into its initial position, comprising a toothed end member secured to said wing, having a pitch line of closed outline including arcuate portions and straight line portions joining the arcuate portions, and having an opening therein, the edge of said opening being parallel to said pitch line, means constituting the pivot and supported on a fixed axis and engaging said edge for supporting said member, and means engaging the teeth of said member for operating said member.

4. Means for operating a movable wing of an airship to produce a downward beating effect and an upward feathering action of the wing alternately, comprising a toothed member for the wing, said toothed member being provided with teeth, the pitch line of said teeth comprising a pair of parallel lines joined at their ends by arcuate lines, a member arranged with its axis fixed and at a predetermined distance at all times from said pitch line for engaging and supporting said toothed member, and means engaging the teeth of said toothed member for operating the same.

5. The combination with a movable wing of an airship, of a toothed gear member comprising a pair of parallel straight racks joined by arcuate racks, the pitch line of said racks, forming the pitch line of said member being a continuous closed line, means arranged on a fixed axis and in predetermined spaced relation to said pitch line for engaging and supporting said member in all positions thereof, and rotatable means in constant engagement with the teeth of said toothed member for operating said member.

6. In an airship, a series of movable wings, and means for operating said wings in timed

relation whereby at least one pair of said wings is operating downwardly to produce a beating effect, comprising a toothed member for each of said wings having a continuous closed pitch line, a stationary pivot for said member, said pivot and said member being relatively movable, and a gear wheel mounted on an axis in fixed relation to said pivot and engaging the teeth of said gear member.

7. In an airship, a wing, a combined support and pivot for the wing, and means for operating said wing for rotational movement downwardly from its substantially vertical initial position wherein the pivot is nearest the lowermost edge of the wing through substantially a half turn into a position wherein the pivot is adjacent the upper edge of the wing and the wing is substantially vertical, and for then moving the wing bodily substantially vertically into initial position, the axis of said support and pivot being stationary relatively to the airship.

8. In an airship, a movable wing, and means for operating said wing continuously, through a downward rotation consisting of substantially a half turn and then bodily upwardly, including a pivot revoluble about a relatively fixed axis, and a member movable with the wing and in constant engagement with said pivot.

9. In an airship, a movable wing, and means for operating said wing continuously, through a downward rotation consisting of substantially a half turn and then bodily upwardly, comprising a toothed member of closed outline and having arcuate ends, at the end of the wing, a gear wheel in continuous engagement with said toothed member, and a support for the toothed member serving as a pivot therefor during the rotational movement of said wing.

10. In an airship, a pair of opposed wings, and means for rotating said wings in opposite directions simultaneously through a substantially semi-circular path and then simultaneously through a substantially vertical path into position for the next rotational movement thereof, each of said wings moving in said semi-circular and vertical paths alternately, said means including a relatively fixed pivot for each of the wings.

11. In an airship, a plurality of pairs of wings, means for moving the wings of a pair simultaneously in opposite directions through a downward rotational movement to balance the airship, and for moving the wings of a pair bodily and simultaneously substantially vertically, in alternation with the rotational movement, said means being timed so that each pair of wings is at a different point in its path at any given instant to produce a continuous upward pressure upon the airship, and including a pivot having a relatively fixed axis.

12. In an airship, a substantially rigid frame, a plurality of pairs of wings mounted for operation in and supported by said frame, and means for operating each pair of said wings at different times continuously alternately through a downward rotational path wherein the tip of the wing moves through a semi-circle of which the wing width is the radius and an upward path wherein the tip 5 moves through a distance equal to the width of the wing, to produce upward pressure upon the airship.

13. In an airship, the combination with a motor, of a substantially rigid frame, a plurality of pairs of opposed wings supported by said frame, and means operatively connected to said motor for operating the wings of a pair simultaneously in opposite directions first through a comparatively rapid 15 downward angular movement of 180° then comparatively slowly and bodily upwardly in the plane of the wing through a substantially vertical path, said pairs of wings being timed to enter their rotational movement at spaced 20 intervals.

14. In an airship, a wing, means for moving said wing alternately through a partial downward rotation and through a substantially vertical path, and means for cushioning the wing upon a change of direction from the rotational movement to the vertical movement.

15. In an airship, a wing, means for moving said wing alternately through a partial 35 downward rotation and through a substantially vertical path, and means for cushioning the wing upon a change of direction from the rotational movement to the vertical movement.

16. In an airship, a substantially rigid frame, a pair of wings mounted for movement in said frame, means for operating each of said wings continuously through a rotational path and an upward path alternately 40 including a pivot having its axis fixed relatively to the airship, and a motor carried by said frame and operatively connected to said means.

17. In an airship, a movable wing symmetrical about the center line thereof, one edge 50 of said wing being curved in a direction opposite to that in which the other edge is curved, and means for operating said wing through a downward rotational path and for then feathering said wing whereby the opposite edges of said wings become operative alternately.

18. In an airship, a wing symmetrical 60 about the center line thereof, and means for operating said wing for partial rotation about one edge thereof and then for upward movement alternately and continuously including a pivot having its axis fixed relative- 65 ly to the airship, said means reversing the

position of the edges of the wing after each complete stroke.

19. In an airship, a wing, means for moving said wing about one edge thereof as a pivot through a partial rotation and for then moving said wing upwardly, and means for cushioning said wing during the latter part of its rotational movement and prior to the upward movement thereof.

20. In an airship, a wing mounted for operation through an angle of substantially 75 180°, and means for operating the wing, comprising an elongated annular toothed member, a gear wheel engaging the teeth of said member, means for rotating the gear wheel, and a support arranged at a fixed distance from the gear wheel and engaging the toothed member for maintaining said member in engagement with the gear wheel, the toothed member being so shaped that on rotation of the gear wheel, the wing is given a movement in a path substantially that of a semi-circle closed by a vertical diameter.
